UNITED STATES PATENT OFFICE.

FRED HEINRICH, OF WHITTEMORE, IOWA.

CHICKEN ROOST.

Application filed April 18, 1922. Serial No. 554,488.

To all whom it may concern:

Be it known that I, FRED HEINRICH, a citizen of the United States, residing at Whittemore, in the county of Kossuth and 5 State of Iowa, have invented certain new and useful Improvements in Chicken Roosts, of which the following is a specification.

This invention relates to new and improved chicken roost including novel means 10 to maintain sanitation and insure proper disinfecting of the roost at all times.

The main object of the invention is to provide a device of the above character which includes a reservoir for the disinfecting fluid, means to properly feed the disinfecting fluid to the upper side of the roost and a novel arrangement of opening whereby the reservoir may be replenished from time to time as the occasion may require.

20 Various other objects of my invention will become apparent during the continuance of the following description.

In the drawings:

Figure 1 is a view in top plan showing my 25 invention in its preferred embodiment, the support being shown in horizontal cross section.

Figure 2 is a view in longitudinal cross section taken on line 2—2 of Figure 1, and

30 Figure 3 is a view in transverse cross section taken on line 3—3 of Figure 1.

In describing my invention in detail, 10 designates the body of the roost which, in the present embodiment is somewhat elongated in form and preferably constructed of 35 wood or other suitable material. A metallic bracket 11 is provided which is fastened to one end and the bottom of the roost by any fastening member 12 and which is designed 40 to support the roost in a horizontal position as is obvious.

The upper side of the roost proper is cut away at 14 to receive spaced inserts 15 which 45 inserts are also preferably constructed of wood or a similar material. Beneath the cut away portion 14 and spaced from the ends thereof the body portion 10 is further cut away to provide a reservoir 16 as clearly 50 shown in Figure 2. In view of the fact that the reservoir terminates short of the ends of 55 the cut away portion 14 it will be noted that the ends of the inserts 15 will be substantially supported upon the shoulders formed between the ends of the reservoir and the ends of the cut away portion 14.

A wick or feeding member 17 is arranged

between the inserts 15 and depends beneath the inserts so as to extend within the reservoir 16. The depending portion of the wick or feeding portion 17 is immersed in the 60 disinfecting fluid that is carried within the reservoir 16 and it will be thereby noted that such disinfecting fluid will be automatically drawn or fed upwardly.

While the insert 15 and the wick 17 are 65 shown maintained in a secure position by means of fastening members 18 it is to be understood that the insert and the wick are removable for purposes of cleaning or substitution or repair and that any other suitable fastening means may be substituted for the means shown in the present instance at 18.

Near one end the inner faces of the insert 15 are provided with cut away portions 19 75 which when arranged opposite each other as shown in Figure 1 provide an opening communicating with the reservoir 16 so that the disinfecting fluid can be poured into the reservoir. I also deem it expedient to provide 80 the body 10 with an opening 20 adjacent one end of cut away portion 14 and also a second opening 21 to establish communication between the opening 20 and the reservoir 16. A disinfecting fluid may be poured into the 85 opening 20 and will find its way into reservoir as is obvious.

It will be noted that a disinfecting fluid will be fed by the wick or feeding member 17 to the upper face of the roost and in such 90 manner as to maintain the roost in a thoroughly sanitary condition and also tend to disinfect the fowl who use the roost.

From the foregoing it is believed that the 95 advantages and novel features of my invention will be readily understood and that further detailed description is unnecessary.

What is claimed is:

1. A chicken roost of the character described, comprising a body portion provided 100 with a cut out portion open to its upper face and a reservoir open to said cut out portion and terminating short of the ends thereof, spaced inserts arranged in said cut out portion, a wick arranged in said inserts and 105 extending into said reservoir, said inserts provided with an opening communicating with said reservoir, and said body portion being provided with an opening spaced from said cut out portion having communication 110 with said reservoir, substantially as described.

2. A device of the character described

comprising an elongated body portion having a cut out portion opened to its upper face, said body portion being further cut away below said cut out portion to provide a 5 reservoir, spaced inserts positioned in said cut out portion a wick arranged between said inserts and depending into said reservoir, the inner faces of said spaced inserts being cut away adjacent one end to provide openings 10 through which fluid may be poured into said reservoir, said body portion being further provided with an opening in communication with said reservoir, and means to support said body portion substantially as described.

3. A chicken roost having a longitudinal

cut out portion open to its upper face and a reservoir beneath said cut out portion terminating short of the ends thereof, removable inserts positioned in said cut out portion and being provided with closed cut outs forming an opening for communication with said reservoir, a wick positioned between said inserts and depending into said reservoir, and said roost being provided with an opening having one end open to said reservoir and the other end open to its upper face, spaced from said first named cut out portion, substantially as described. 20 25

In testimony whereof I affix my signature.

FRED HEINRICH.
